(57) **CLAIM**

The ornamental design for a biplane toy, as shown and described.

DESCRIPTION

FIG. 1 is a top front isometric view of a biplane toy showing my new design;

FIG. 2 is a bottom rear isometric view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

In the drawings, the broken lines depict portions of the biplane toy that form no part of the claimed design.
